(57) **CLAIM**

The ornamental design for a hot toaster oven rack push/pool
tool, as shown and described.

DESCRIPTION

FIG. 1 is a front view of a hot toaster oven rack push/pull tool
showing my new design, the opposite side being a mirror
image.

FIG. 2 is a side view thereof.

FIG. 3 is an upper end view thereof; and,

FIG. 4 is a lower end view thereof.
